UNITED STATES PATENT OFFICE.

WILLIAM E. BUDD, OF CHATHAM, NEW JERSEY.

HARROW.

SPECIFICATION forming part of Letters Patent No. 293,304, dated February 12, 1884.

Application filed October 5, 1883. (No model.)

To all whom it may concern:

Be it known that I, WILLIAM E. BUDD, of Chatham, in the county of Morris and State of New Jersey, have invented certain new and useful Improvements in Harrows; and I do hereby declare the following to be a full, clear, and exact description of the invention, such as will enable others skilled in the art to which it pertains to make and use it, reference being 10 had to the accompanying drawings, which form part of this specification.

My invention relates to an improvement in harrows; and it consists, first, in the combination of the harrow provided with the pivoted 15 adjustable bearings at its rear end, the bolts which secure the bearings to the harrow, the brackets and set-screws for controlling the movement of the bearings, the roller which is journaled in the bearings, and the pivoted 20 seat-frame provided with a roller; second, in double-edged harrow-teeth which are provided with shoulders to catch under the lower edges of the beam, and suitable projections to catch in recesses formed in the sides of the 25 beam, and suitable clamping bolts or devices for holding them in place, whereby when one edge of the tooth has become dulled the edges may be reversed by applying the teeth upon the opposite side of the machine; third, in an 30 adjustable seat, the lever upon which the seat is placed, an arm or brace secured to the under side of the lever, and which is provided with a friction-roller at its lower end to bear upon the roller which is attached to the rear 35 end of the frame, all, of which will be more fully described hereinafter.

Figure 1 is a plan view of a harrow embodying my invention. Fig. 2 is a side elevation of the same. Figs. 3, 4, 5 are detail views of 40 the same.

A represents the harrow-frame, which is composed of the short front piece, B, the rear piece, C, and the diagonal beams D. These diagonal beams D are divided into two sets, 45 which run parallel with each other, but at an angle to the other set, as shown. The outer ends of these beams D do not cross each other; but the two central ones intersect each other at any suitable distance in the rear of the front 50 piece, B, as shown in Fig. 1. To the sides of these beams D are secured the teeth E, and in

such relative arrangement to each other that they harrow the ground evenly, as shown in dotted lines. Each one of these teeth is provided with two cutting-edges, a shoulder, F, 55 to catch against the under side of the beam D, to which it is attached, and a projection, G, which catches in a suitable recess made in the side of the beam at any suitable distance above its lower edge. Each tooth, after being applied 60 to the side of the beam D, is then clamped rigidly in position by means of a clamping-bolt, H, or other suitable fastening device. When the front edges of the teeth have become dulled, it is only necessary to remove them 65 and apply them to beam upon the opposite side of the harrow, when the rear edges will be brought into play. By this means the teeth can be used to advantage a much longer time than can be done if they were provided with 70 a single cutting-edge only.

In order to use the harrow as a furrow-opener or a combined furrow-opener and harrow, there will be attached to the beams D the furrow-opener Z, as shown in Fig. 2. These 75 furrow-openers consist of bent bars or rods, which are perforated at their ends, so as to be adjustable vertically in relation to the beams to which they are attached, and to this bar is attached a suitable furrow-opening device of 80 any desired construction. These furrow-openers Z do not extend parallel with the beams D, but have their front ends attached to one beam and their rear ends to the next adjoining beam, as shown in Fig. 1. The number 85 of furrow-openers used will depend upon the size of the harrow. Upon an ordinary harrow, such as is shown in Fig. 1, only two of the openers will be used. These furrow-openers are made vertically adjustable, so that the 90 harrow can be raised upward to such a distance that the harrow-teeth will not touch the ground; or the furrow-opener may be raised upward to such a distance that the teeth will harrow the ground at the same time that the 95 furrow is being opened. Pivoted upon the top of the cross-beams D, near the front edge of the harrow, is the pivotal rod or bar I, to which the upright J is secured. To the upper end of this upright J is rigidly secured the 100 seat-lever L. To the under side of this seat-lever is secured the rigid frame or brace N,

which is provided with a friction-roller, O, at its lower end. The seat P is provided with the two depending flanges Q, which have their lower ends turned inward for the purpose of catching underneath the bar L, and this seat is made adjustable back and forth upon the bar for the purpose of enabling the driver to put his weight upon any desired part of the harrow. By means of a set-screw which is passed through one of the flanges Q, the seat can be readily secured at any desired point.

When the ground is to be rolled at the same time that it is harrowed, the removable roller R will be applied to the rear end of the harrow, as shown in Fig. 1. For this purpose the metallic levers S are pivoted to the beams D at their front ends by means of bolts T, and held in any desired relation at their rear ends to the outer sides of the beam D by means of the brackets U, which are bolted to the beams by means of the bolts V, which pass vertically down through the beams D. Through the outer sides of these brackets are passed the set-screws W, which have their inner ends catch 25 in any one of a series of holes which are made through the levers S. By means of this series of holes the levers S can be adjusted up and down, so as to bring a greater or less pressure of the roller upon the ground, as may be desired.

The set-screws W can be removed at any time, and then the roller will rise and fall with the irregularities of the surface of the ground under the pressure of the driver's weight.

To the rear ends of the metallic levers S will be secured wooden blocks, in which the journals of the roller will turn. These blocks can

be readily removed when worn out and replaced by others. The friction-roller O of the arm or brace N bears upon this roller R for 40 the purpose of causing the roller to break and crush the clods.

It will be seen that this harrow will harrow and roll the ground, or will harrow and open the furrows, or will simply harrow alone, as 45 may be desired.

Having thus described my invention, I claim—

1. The combination of a harrow having a series of beams, D, which have recesses made 50 in their sides where the teeth are to be applied to them, with the teeth provided with the shoulders F and studs or projections G, and the clamping-bolts H, whereby the teeth are made removable from one side of the harrow 55 to the other, so that their cutting-edges can be reversed, substantially as specified.

2. The combination, in a harrow, of the seat-lever L, the adjustable seat attached thereto, an arm or brace, N, the friction-roller O, and the roller R, which is attached to the rear end 60 of the harrow by means of the adjustable levers S, substantially as shown.

3. The combination of the harrow, provided with the pivoted adjustable bearings S at its 65 rear end, the bolts T, brackets U, set-screws W, roller R, the pivoted seat-frame L M J, and the roller O, substantially as described.

In testimony whereof I affix my signature in presence of two witnesses.

WM. E. BUDD.
